UNITED STATES PATENT OFFICE.

JOHN M. SWEENEY, OF PORTLAND, OREGON.

WATER-CLOSET.

1,097,569.

Specification of Letters Patent.

Patented May 19, 1914.

Application filed May 12, 1913. Serial No. 767,234.

To all whom it may concern:

Be it known that I, JOHN M. SWEENEY, a citizen of the United States, residing at Portland, in the county of Multnomah and State of Oregon, have invented certain new and useful Improvements in Water-Closets, of which the following is a specification.

This invention relates to improvements in water closets, and has for its object to provide means whereby all communication between the premises and the depository is effectually cut off, both when in use and when not being used.

A further object is to provide means for depositing a quantity of disinfecting water in the bowl where it will flush and deodorize the bowl after use.

These and other objects are accomplished by the means illustrated in the accompanying drawings in which—

Figure 1 is a plan view of closet equipped with my improved device, with the bowl open. Fig. 2 is a vertical sectional view taken on the line A—A, of Fig. 1, with the bowl closed. Fig. 3 is a similar view taken on the line C—C of Fig. 1. Fig. 4 is a fragmentary side elevation with parts broken away to show the interior structure. Fig. 5 is a front elevation with bowl closed. Fig. 6 is a fragmentary detail view showing the manner of seating the united parts. Fig. 7 is a vertical sectional view showing the inlet valve. Fig. 8 is a cross sectional view thereof taken on the line B—B, of Fig. 7. Fig. 9 is a top view of a part of Fig. 7.

Referring to the drawings in detail, 1 represents a metallic casing or tank contiguous to the wall 2, of any suitable room and extending through the floor 18. Within this 40 casing is mounted the swinging bowl 3, to swing upon the pivots 23 formed on the bowl and bearing in suitable apertures in the flange casting 21 secured about the edge of the opening of the casing 1, and into 45 which the bowl is fitted; and by means of a facing 20, the opening will be sealed to prevent the escape of gases.

At one side of the bowl, at the inner or rear end, is formed a tank 4, which has an 50 open side 4^a. The remainder of the rear portion of the bowl is projected rearwardly a considerable distance, and it has an open rear side which is closed by means of a trap door 5, hinged upon the pin 6. This door 55 will be made of heavy casting and its weight will hold it firmly closed, which will prevent

the entrance of gases from the tank when the bowl is swung into horizontal position, for use. The bottom 3^a of the outlet portion of the bowl is formed on a lower plane than the remainder, so that when it is tilted forward from the position seen in Fig. 2, to that in Fig. 3, the disinfecting water carried in the tank 4 will flow out and moisten the bowl, which will prevent particles coming in contact therewith from sticking to its surface. It will also neutralize odors therein and it will flush the bowl, when it is tilted back to the position seen in Figs. 2 and 4, allowing the contents to drop through the door 5 into the tank 1 below. Within the tank or casing 1, to the rear of tank 4, is secured another tank 7, adapted to be fed from its bottom through the pipe 27, and which is provided with a vent 25 having an outlet at a point which is higher than the source of supply. A pipe 29 leads from the source of supply into the tank 1, and it has formed upon its end a valve casing 9, in which is seated the valve 33 having an inlet 80 opening 36 adapted to register with opening 35 leading from said pipe 29. Upon the upper portion of the valve plug is formed at right angles thereto, the pipe 8, and into the upper portion of the valve plug is seated another valve plug 32 having an outlet opening 34 adapted to register with the outlet pipe 8. In the outer end of the valve plug 32 is fitted said pipe 27 which is sustained by the bracket 30 fixed upon the pipe 29, 90 and the spring 31 holds the plug 32 firmly in its seat.

When the bowl is in vertical position, as seen in Fig. 2, the pipe 8 will be drawn down to overhang its rear wall by the spring 11 95 acting upon the arm 10 formed at right angles to said pipe, upon the valve plug 33, thereby shifting the opening 36 from registration with opening 35 and cutting off the water supply, and at the same time turning 100 the plug 33 so that pipe 8 will register with opening 34, which will permit the water from tank 7 to flow into the upturned tank 4, where it will remain until the bowl is desired for use again. Upon swinging the 105 bowl to horizontal position the rear wall 4 will bear against the adjustable arm 38 to swing the pipe 8 upwardly as seen in Fig. 3, cutting off communication therethrough, and establishing communication with the inlet pipe 29, allowing the tank 7 to refill. As 110 the bowl swings to upright position the

angular portion 16 will contact with the correspondingly formed flanged portion 14 secured upon the casing 1, which flange is provided with a facing 15 to form a gas-tight joint as seen in dotted lines 3^b; and when in open position the seat 22 of the bowl will rest upon the facing 12 on the upper face of flange 14, and the upper side of tank 14 will tightly close against the facing 20 on the flange 21.

39 is an outlet pipe from tank 1 leading to a cesspool or other outlet.

40 is a handle secured upon the front of the bowl by means of which the bowl may be raised and lowered. To the front edge of the bowl also is pivotally secured an arm 13, adapted to engage the catch 19 to securely lock the bowl in closed position.

A cover 24 hinged at 24^a in position to seat upon the bowl when lowered is provided with a central seat opening 28.

By means of the structure here shown I have provided a closet adapted for the use of buildings having no sewer system though it may be employed in connection with such system. The device is equally adapted to use upon railway cars, ships, etc.

Having now described my invention what I claim is—

30 1. A bowl for water closets, comprising a body portion having bearings at its median point for pivotal mounting, said bowl being open at one side, the opposite side expanding toward its central portion, a compartment formed in one side of the lower end portion of the bowl whose upper-side opens into and is continuous with the body thereof, and a sluice way formed in the opposite side of said lower end adjacent said compartment.

40 2. The combination of a casing which is open at its front upper corner, and is provided with seats about the opening thereof, with a bowl mounted by a median point within the front edge of the casing adapted to swing from horizontal to vertical position and forming a finished closure for said opening, seats formed upon the bowl adapted to fit and close upon seats about said

opening when in vertical position, and similar seats for closing the opening when the bowl is in horizontal position.

3. The combination of a casing which is open at its front upper corner, with a bowl open at one side and expanding at the other mounted by a median point within the front edge of the casing, adapted to swing from horizontal to vertical position and forming a finished closure for said opening, means by which the spaces between the bowl and casing are sealed in either horizontal or vertical position, a compartment formed in one side of the lower end portion of the bowl whose upper side opens into and is continuous with the body thereof, and a sluice-way leading from said expanded portion adjacent said compartment opening at the lower end of the bowl.

4. The combination of a casing which is open at its front upper corner, with a bowl open at one side and expanding at the other mounted by a median point within the front edge of the casing, adapted to swing from horizontal to vertical position and forming a finished closure for said opening, means by which the spaces between the bowl and casing are sealed in either horizontal or vertical position, a compartment formed in one side of the lower end portion of the bowl whose upper side opens into and is continuous with the body thereof, a sluice-way leading from said expanded portion adjacent said compartment opening at the lower end of the bowl, a tank within the casing, an outlet pipe therefrom, a cut-off valve in said outlet, and an outlet pipe fixed to said cut-off and yieldingly held in communication with said compartment, whereby when the bowl is in vertical position the cut-off will be opened to transfer the contents of the tank to the compartment, and when in horizontal position the cut-off will be closed.

In testimony whereof, I affix my signature in presence of two witnesses.

JOHN M. SWEENEY.
